UNITED STATES PATENT OFFICE.

HOWARD L. FISCHER AND JOHN W. DAHLGREN, OF ST. PAUL, MINNESOTA, ASSIGNEES
TO FRED'K G. BRADBURY, OF ST. PAUL, MINNESOTA.

GRAVITY-CARRIER SWITCH.

1,071,636.

Specification of Letters Patent. Patented Aug. 26, 1913.

Application filed October 12, 1907. Serial No. 397,239.

To all whom it may concern:

Be it known that we, HOWARD L. FISCHER and JOHN W. DAHLGREN, citizens of the United States, residing at St. Paul, in the 5 county of Ramsey and State of Minnesota, have invented a new and useful Improvement in Gravity-Carrier Switches, of which the following is a specification.

Our invention relates to improvements in 10 gravity carrier switches and has for its object a switch for use in connection with gravity carriers which is adapted to be thrown into and out of operation for the purpose of conveying articles of merchandise by 15 gravity from a main carrier to a branch carrier.

Among further objects are simplicity of construction, effectiveness in use, and means for throwing the switch into and out of operation from a station remote from said switch.

In the accompanying drawings forming 20 part of this specification, Figure 1 is a plan view of our invention showing a switch between a main gravity carrier and a branch gravity carrier; Fig. 2 is a side view of Fig. 1; Fig. 3 is a sectional view taken on the line X—X of Fig. 1; Fig. 4 is another section of Fig. 1 taken on the line Y—Y; 25 Fig. 5 is a plan view showing a system of gravity carriers employing our improved switch; Fig. 6 is an enlarged detail view of a portion of the operating mechanism for the switches shown in Fig. 5; Fig. 7 is a detail view of one of the brace rods, and Figs. 30 8 and 9 are detail views of other brace rods.

In the drawings A represents a main gravity carrier slanting downwardly in the direction of the arrows shown, and B a 35 branch gravity carrier also slanting down in the direction of the arrow indicated. The branch gravity carrier is arranged substantially at right angles to the main carrier, although it can be placed at any angle 40 desired. Between the main carrier and the branch carrier is our improved gravity carrier switch C.

The main and branch carriers consist of 45 side rails 2 and 3 which are spaced apart by transverse bars 4 and braced by stay rods 4' to hold the rails rigidly apart. Journaled upon the inner faces of these rails by means of stud bolts 5 are longitudinal series of 50 anti-friction wheels 6 which run upon ball bearings (not shown) between said parts in

the usual manner. A short series of anti-friction wheels on the outer rail 2 of the main gravity carrier adjoining the outer rail 7 of the switch are journaled by said stud bolts upon the outer face of said rail 60 as shown.

The switch C comprises a pair of rails 7 and 8 which are equally spaced apart by transverse rods 9 and curved as shown between the rails of the main gravity carrier 65 and the ends of the rails of the branch gravity carrier. Each space rod 9 is pivoted at one end by a ball and socket joint 9' to the rail 8 and rigidly secured at the other end to the rail 7 by means of lock 70 nuts 9''. Upon the outer faces of the rails 7 and 8 are series of anti-friction wheels 10 which are journaled upon stud bolts 11 by means of ball bearings (not shown) in the usual manner. The inner rail is secured at 75 its ends to the rail 3 of the main carrier and branch carrier by means of bolts 12 so that the anti-friction wheels thereon form a continuous carrying surface between the main and branch carrier. The outer rail 7 has 80 one end pivotally secured to one of the transverse space bars 4 of the main carrier by means of the pivot bolt 13 and its other end free to be raised and lowered and guided in its movement in the standard 14. When 85 in elevated position the outer rail 7 has the portion intermediate of its ends raised with its anti-friction wheels above the level of the anti-friction wheels of the rail 3 of the main carrier so that articles approaching the 90 switch on the main carrier will be carried by said curve onto the branch carrier.

The means for raising and lowering the outer rail of the switch consists of a longitudinal shift rod 15 which slides back 95 and forth in vertical guides 16 below the switch. These guides are bolted or otherwise fastened to the floor by means of the bolts 17 and are pressed together by means of the rod 18. Below the lower edge of the 100 shift rod in the guides are anti-friction wheels 19 which reduce the friction between the shift rod and said guides. Upon the inner face of the outer rail 7 of the switch are a pair of anti-friction rollers 20 which are suitably journaled upon stud bolts 21 extending into said rail. These wheels run upon the upper edge of the shift rod and serve to support the outer rail 7 of the 105 switch. The upper edge of the shift rod 110

is formed with a pair of inclined edges 22 extending together in one direction to elevate the outer rail of the switch when the shift rod is thrown forward and to allow the outer rail of the switch to lower when the shift rod is reversed. The shift rod is moved forward and backward by means of a pivoted handle 39 coöperating with a toothed segment 23 and interlocked therewith by means of the dog 24. The handle 39 is pivotally connected to the shift rod by means of a link 25. The outer rail 7 is looped down at 26 below the rail 3 of the main carrier so that when raised and lowered, the outer rail of the switch will not interfere therewith. When the shift rod is thrust ahead the outer rail of the switch is raised above the rail 3 of the main carrier and articles of merchandise moving downward upon the latter are intercepted by the switch and pass onto the branch carrier.

In Fig. 5 we have shown a plurality of switches used in connection with our main carrier and connecting with branch carriers. In this construction as in the construction already described A denotes the main carrier, B the branch carriers and C the switches between the main carriers and the branch carriers. These switches are arranged to be operated from a single point and are shifted backward and forward by means of a bell crank lever 30 pivoted upon a standard 31 adjoining each switch. The link 25 of the shift rod is pivoted to one arm of the bell crank lever and a cable 32 is attached to the arm of said lever and to an operating lever arm 33. All of the operating lever arms 33 are located at a single station 34 from which point any or all of the switches can be thrown into and out of operation.

The means for returning the switches to lowered position and throwing them out of operation consists of a spring 35 attached to the arm 33 of the bell crank lever and to a fixed support 36 adjoining said arm. In this manner the switches are returned to normal position automatically.

In Fig. 6 the bell crank lever is pivoted at its angle upon a support 37 which is formed with an extension 38 to which one end of the spring 35 is attached, instead of to the fixed support 36 as illustrated in Fig. 5.

It is obvious that the angle of inclination of the main, branch and switch carriers may be reversed without departing from the spirit of this invention and of the following claims.

In accordance with the patent statutes, we have described the principle of operation of our invention, together with the apparatus which we now consider to represent the best embodiment thereof, but we desire to have

it understood that the apparatus shown is only illustrative and that the invention can be carried out by other means and applied to uses other than those above set forth, within the scope of the following claims.

Having described our invention, what we claim as new and desire to protect by Letters Patent, is:—

1. A gravity carrier, comprising, in combination, a pair of carriers and a carrier switch between them, all of said parts being inclined in the general direction of run of the material to be carried thereon, said switch consisting of outer and inner rails, a series of antifriction wheels or rollers journaled upon said rails, one of said rails being stationary and the other movable up and down, and a shift adjacent said movable rail adapted to raise and lower it into and out of operation, for the purposes specified.

2. A gravity carrier system, comprising, in combination, a main gravity carrier, a plurality of branch gravity carriers, and a gravity carrier switch for each of said branch carriers, all of said parts being inclined in the general direction of run of the material to be carried thereon; said gravity carrier switch comprising outer and inner curved rails, series of antifriction wheels or rollers journaled upon said rails, the outer rail being pivotally mounted to swing up and down and the inner rail stationary, and a shift adjacent the outer rail for raising and lowering it into and out of operation, for the purposes specified.

3. A gravity carrier, comprising, in combination, a pair of carriers and a carrier switch between them, all of said parts being inclined in the general direction of run of the material to be carried thereon, said switch consisting of outer and inner rails, a series of antifriction wheels or rollers journaled upon said rails, one of said rails being pivoted to swing up and down and the other immovable, a shift arranged to raise and lower said pivoted rail, and means for operating said shift, for the purposes specified.

4. A gravity carrier system, comprising, in combination, a main gravity carrier, a plurality of branch gravity carriers, a gravity carrier switch for each of said branch carriers, all of said parts being inclined in the general direction of run of the material to be carried thereon; said gravity carrier switch comprising outer and inner curved rails, series of antifriction wheels or rollers journaled upon said rails, the outer rail being movable up and down and the inner rail immovable, and a shift adjacent the outer rail for raising and lowering it into and out of operation, and a plurality of operating means for independently moving a shift to operate any one of said switches from a single point.

5. In a gravity carrier system, a pair of side rails spaced apart, a series of antifriction wheels or rolls mounted upon said rails and a spacing rod between said rails, one 5 end of said rod being pivoted to one of said rails and immovably fixed to the other.

6. Apparatus of the class set forth, comprising, a main gravity carrier, a branch gravity carrier, and a gravity carrier switch, 10 all of said parts being inclined in the general direction of the run of the material to be carried thereon; said gravity carrier switch consisting of outer and inner curved rails, series of anti-friction wheels journaled upon

said rails, the outer rails being pivotally connected with the inner rails to swing up and down, and a shift below the outer rail for raising and lowering it into and out of operation, for the purposes specified. 15

In testimony whereof, we have signed our 20 names to this specification, in the presence of two subscribing witnesses.
